TRAVELER'S BELT
Royace H. Pipkin, P.O. Box 1615, Raleigh, N.C.
Filed July 15, 1958, Ser. No. 748,683
3 Claims. (Cl. 2—301)

This invention relates to a belt which is convertible to a coat hanger.

The object of this invention is to provide a belt which is convertible between a belt and coat hanger so that the belt serves the double purpose.

Often travelers find lodgings without coat hangers making it quite difficult to keep the clothes orderly or at least, quite annoying to try to do so. The invention solves this problem by a specially constructed belt having means by which to hold a portion of the belt rigid against movement in one direction so that the belt can be shaped approximately in the form of a triangle with the tongue end of the belt equipped with a hook or made to function as a hook for hanging the belt, now in coat hanger formation, so that it can receive garments of any type.

A further object of the invention is to provide a practical device capable of converting between use as a belt and use as a coat hanger. When used as a belt, there is no characteristic marking which would identify the belt from other conventional belts. In other words, it looks very much like if not identical to an ordinary belt when used as such. Part or all of the mechanism by which to convert between the belt and coat hanger functions, is concealed and when worn, all of the mechanism is concealed.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is an elevational view of a belt of this invention showing the belt oriented to function as a coat hanger.

Figure 2 is a fragmentary plan view, parts broken away, of the central part of the belt showing the mechanism by which to retain parts of the belt rigid against movement in one direction.

Figure 3 is an enlarged elevational view of the buckle of the belt.

Figure 4 is a bottom plan view of the buckle of the belt.

Figure 5 is an elevational view of the tongue end of the belt showing a collapsible hook that is suggested for hanging the belt when functioning as a coat hanger.

Figure 6 is a sectional view taken on the line 6—6 of Figure 2.

Figure 7 is a fragmentary sectional view taken at right angles to the plane identified at 6—6 but showing only the hinge construction.

In the accompanying drawings there is a convertible belt 10 to exemplify the principles of the invention. The belt selected for illustration is a two-ply belt having plies or panels 12 and 14 jointed at their longitudinal edges by rows 16 and 18 of stitching. In this type of belt the means 20 for enabling the belt to function as a coat hanger, can be completely concealed. These means are located in the pocket 22 formed between panels 12 and

14, although it is to be understood that means 20 need not be completely concealed. For single ply belts, the same means 20 can be attached to the inner surface of the single panel or ply from which the belt is made.

5 One end of belt 10 has a special buckle 26 thereon. The buckle prong 28 is special in the sense that it has a file 30 on one surface thereof. In addition, there is a short panel 32 attached to the frame 34 of the buckle, the frame being approximately rectangular whereby the 10 buckle frame and panel 32 cooperate to form a bottle opener.

The tongue end 36 of the belt has a hook 38 attached to it and on the surface of the belt that would face the wearer, whereby hook 38 is ordinarily concealed. The 15 hook has a shank 40 attached by rivet 42 or some other fastener, to the belt end 36. The bill 44 of the hook is made in two sections connected together by hinge pin 46. A small arm 50 protrudes from one of the sections and is adapted to engage the other of the sections so that the 20 hinged movement between the sections of the bill of the hook has a limit established by arm 50 striking the adjacent section of the bill. The full open position of the hook is shown in dotted lines in Figure 5. To hold the hook in place when it is not being used as such, a small 25 spring clip 52 attached to end 36 of the belt, receives the pivoted end section of the bill of the hook, holding it in place.

The previously referred to means 20 are flexible when moved in one direction but become rigid when moved 30 beyond a predetermined point in the opposite direction of movement. This is necessary so that when the belt is used around the waist of an individual, it will flex properly to encircle the waist of the person. But, when used as a coat hanger the necessary rigidity exists. The means 35 20 shown in Figures 2, 6 and 7 are limited to the central or back part of the belt by transverse rows of stitching and constructed of a chain of hinged members with the hinges capable of being moved in one direction (see Figure 7) but incapable of being moved in an opposite 40 direction with respect to each other. Typical member 60 is made of a flat plate that is substantially T-shaped at one end when viewed from above (Figure 2). It has a wider part 62 and a narrower part 64 extending from one of the longer edges of wider part 62. Sleeve 66 extends 45 transversely across part 64, and there is a stop 68 protruding laterally from sleeve 66. A pair of sleeves 70 and 72 having their longitudinal axes in alignment, and spaced from each other, are on the longer edge of part 62 opposite to that edge from which part 64 extends. 50 Hinge pin 74 is passed through the aligned sleeves 70 and 72 and through a sleeve 78 of the adjacent member, sleeve 78 being the same as sleeve 66 in construction and function. The adjacent member 80, being constructed identical to member 60, has a stop 82 which fits over a 55 surface of member 60 enabling the member 80 to swing or hinge about pin 74 in one direction only. That is, stop 82 limits the amount of motion that members 60 and 80 can have between them. It can move to a position where they are approximately coplanar and from this 60 position can move in one direction only, this being sufficient to enable the belt to be placed around the waist of a person to serve the usual belt function.

Sleeve 66 of member 60 is disposed between the spaced 65 sleeves 84 and 86 of member 88. The member 88 is also adjacent to member 60 and on the opposite side thereof from member 80. Hinge pin 90 is passed through the two sleeves 84 and 86 that are aligned with each other, and through the sleeve 66 of part 64 of member 60 thereby hingedly connecting the members 60 and 88 in the 70 same way that members 60 and 80 are connected. Stop 68 abuts a surface of member 80, also limiting the pivotal movement of the members 60 and 80 just as stop 82.

limits the pivotal movement between members 60 and 80.

Although numerous means may be used to attach the means 20 to the belt, the pocket walls formed by panels 12 and 14 serve as a fastening device for means 20.

When used as a coat hanger, the conversion between the belt and the coat hanger entails only the following: Belt 10 is placed on a table or some other supporting surface and outstretched with the inner surface facing downwardly. Tongue end 36 is inserted up through the inverted buckle frame 34 and engaged with the tongue 28 which prevents the buckle frame 34 from sliding downwardly. Hook 38 is unfastened and is made ready for use. The center section 93 of the belt containing means 20 is held flat on a supporting surface while the two sides 94 and 95 are hinged beyond pocket 22 in the regions 96 and 97. The means 20 prevents flexing of section 93 except in a direction which the specially constructed means 20 will allow. The portions 94 and 95 of the belt between regions 96, 97 and the buckle do not move inwardly toward each other or toward the section 93 because they are held taut by the weight and rigidity of section 93 while the hanger is suspended.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A belt construction adapted to be converted from a waist encircling belt to a garment hanger comprising an elongated flexible panel having a buckle at one end and means on the other end for detachable engagement with the buckle, a portion of said panel including means for preventing flexing thereof in one direction for forming a rigid bottom of a triangle formed when the panel is suspended from a support connected with the joined free ends thereof with the inner surface of the panel, when used as a belt, facing outwardly whereby said

means for preventing flexing in one direction is rendered effective to prevent downward flexing of the bottom of the triangle, said portion of the panel flexing in the flexible direction thereof when encircling the waist of a wearer.

5 2. The belt construction as defined in claim 1 wherein said means for preventing flexing in one direction includes a plurality of links hingedly attached to each other, each of said links including a projecting stop on one end thereof for engagement with an adjacent link for limiting the pivotal movement in one direction while permitting pivotal movement in the other direction.

10 3. A belt construction adapted to be converted from a waist encircling belt to a garment hanger comprising an elongated flexible panel having a buckle at one end and means on the other end for detachable engagement with the buckle, a portion of said panel including means for preventing flexing thereof in one direction for forming a rigid bottom of a triangle formed when the panel is suspended from a support connected with the joined free ends thereof with the inner surface of the panel, when used as a belt, facing outwardly whereby said means for preventing flexing in one direction is rendered effective to prevent downward flexing of the bottom of the triangle, said portion of the panel flexing in the flexible direction thereof when encircling the waist of a wearer, the other end of the elongated flexible panel being provided with a foldable hook normally disposed in concealed relation within the area defined by the 15 panel and adapted to be unfolded into operative position for engagement with a support thus suspending the structure when in the form of a coat hanger.
